UNITED STATES PATENT OFFICE.

GEORGE KEARNEY BRADFIELD, OF HACKENSACK, NEW JERSEY, ASSIGNOR TO
VACUUM OIL COMPANY, OF ROCHESTER, NEW YORK, A CORPORATION OF NEW
YORK.

LAMP.

1,050,913.

Specification of Letters Patent. Patented Jan. 21, 1913.

Application filed April 20, 1912. Serial No. 692,174.

To all whom it may concern:

Be it known that I, GEORGE KEARNEY BRADFIELD, a citizen of the United States, and resident of Hackensack, in the county 5 of Bergen and State of New Jersey, have invented certain new and useful Improvements in Lamps, of which the following is a specification.

This invention relates to lamps in which 10 wax or wax-like solid illuminants may be burned.

In a wax-burning lamp, since the illuminant, when the lamp is not in use, is in solid condition, the wick-tube and wick cannot 15 be withdrawn from the body of the lamp at this time, and accordingly the wick-tube is commonly attached permanently to the bottom of the lamp, particularly as this construction permits the heat of the flame to be 20 transmitted effectively to the bottom of the wax-receptacle, so as to melt the wax therein when the lamp is burning. In a lamp of the construction just described it is necessary for the wick to issue from the side of the 25 wick-tube near the lower end thereof, and, since the wick must bend sharply at this point, more or less difficulty is encountered in inserting a wick.

The object of the present invention is to 30 provide a wax-burning lamp with a fixed wick-tube having a lateral outlet near its lower end, this wick-tube being so constructed as to facilitate the introduction of the wick, and to this end I provide the wick- 35 tube with one or more deflecting-members adjacent the lateral outlet, which are adapted to guide the end of the wick through the outlet, these members being formed and arranged in the novel manner hereinafter de- 40 scribed and claimed.

In the accompanying drawings:—Figure 1 is a vertical, median section of a lamp embodying the present invention; and Fig. 2 is a horizontal section on the line 2—2 in 45 Fig. 1.

The general form of the illustrated embodiment of the invention is not novel. The lamp comprises the usual cylindrical wax-receptacle 5 with a flat bottom 6 and a top 7. The wax is introduced through a central opening in the top, which is normally closed by a cover 8.

The wick-tube is formed of two channel-shaped sheet-metal members, one of these 55 members comprising a flat web 9 with lateral

flanges 10, and the other comprising a similar web 11 with lateral flanges 12. These channel-members are placed together, with the back of the first closing the front of the second, the two members being soldered or 60 otherwise fixed together so as to form between them a passage for the wick, while the flanges 10 act to stiffen and reinforce the tube. The channel-members are provided, respectively, at their lower ends with 65 members 13 and 14 bent into horizontal position and soldered upon the bottom 6 of the wax-receptacle, so as to fasten the wick-tube permanently in place.

To permit melted wax to be absorbed by 70 the wick, the parts 9 and 11 of the wick-tube are provided with perforations 15 through which the wax may flow.

The heat of the flame is conducted downwardly through the wick-tube so as to melt 75 the wax in the usual manner, and to facilitate this action a metal heat-conductor 16 is arranged to partly surround the flame, this heat-conductor having downwardly-extending portions 12 which are inserted within 80 the wick-tube adjacent the edges of the wick 18, as shown in Fig. 2. A wick-raiser 19 of ordinary form is provided, as shown in Fig. 1.

To provide the lateral outlet for the wick, 85 near the lower end of the wick-tube, the part 11 is cut or slotted horizontally, and the sheet-metal above and below this cut is bent, respectively, outwardly and inwardly so as to form guide-members or deflectors 20 and 90 21, respectively. The deflector 21 extends across the passage in the wick-tube between the flanges 12, so that when the wick is introduced in the tube the lower end of the wick, upon engaging this deflector, is directed 95 downwardly and outwardly so as to emerge freely from the tube into the position of Fig. 1, and for this reason it is necessary, in introducing the wick, merely to push the end of the wick into the upper end 100 of the wick-tube, and then rotate the wick-raiser 19 to lower the wick. When the wick-raiser is turned to raise the wick, on the other hand, the deflector 20 causes the wick to return freely into the tube, a sharp angle 105 above the wick-outlet being eliminated by the presence of this deflector.

I claim:—

1. A wax-burning lamp having, in combination, a wax-receptacle, and a wick-tube 110

fixed, at its lower end, to the bottom of the receptacle and extending upwardly through the top of the receptacle, the material of one side of the wick-tube, near the lower end thereof, being cut horizontally and inclined outwardly and inwardly above and below the cut, respectively, so as to provide inclined deflectors to guide the wick through the lateral outlet so formed.

10. 2. A wax-burning lamp having, in combination, a wax-receptacle, and a wick-tube fixed, at its lower end, to the bottom of the receptacle and extending upwardly to the

top of the receptacle, the wick-tube comprising two channel-shaped members fixed together with the back of one closing the front of the other, the back of the latter member being cut across, and the metal below the cut inclined inwardly to form a deflector inclosed between the flanges of said member and adapted to guide the wick outwardly from the wick-tube. 15
